PAPER RULING MACHINE

Charles E. Clarke, Winchester, and Robert T. Duffy, Boston, Mass., and Joseph W. Cloutier, Franklin, N. H., assignors to Lindbladh Corporation, Boston, Mass., a corporation of Massachusetts

Application July 31, 1939, Serial No. 287,552

19 Claims. (Cl. 33—39)

This invention relates to paper ruling machines of the general type disclosed in U. S. Letters Patent No. 1,813,940 granted July 14, 1931, on an application of H. E. Lindbladh. More particularly, this invention consists in a combination of improvements in ruling machines, by means of which the rate of production can be materially increased over that obtained from previous machines available to the industry.

Paper ruling machines as usually constructed include in their structure a great number of moving elements such as trains of gears, cams, rollers, and levers, and it has heretofore been impossible to operate available ruling machines at a speed producing more than about four reams of ruled paper an hour, because at higher speed the momentum of the moving elements creates vibration and irregularity of movement interfering with accurate pen control and sheet movement and location. Accordingly, the primary object of our invention is to provide an improved machine which will rule from 6 to 10 reams of paper an hour with perfect accuracy of ruling operation.

We have found that a ruling machine of the Lindbladh type can be built to operate successfully at a high rate of production if modified in four important respects as compared to prior machines. In the first place, we propose to eliminate the heavy pen beam formerly employed and to modify and lighten the pen clamp and secure it directly to the usual rock shaft. In the second place, the cams operating the pen clamp and underlifts are arranged merely to raise and lower the clamp and independent means is provided for maintaining the clamp and pens in raised position, thus eliminating the conventional "fill in" cams. Thirdly, a lay boy of novel construction is provided which is arranged to spread the sheets as they are delivered and to stiffen them against buckling by imparting a longitudinal curvature to them. Finally, a Reeves variable speed transmission, directly driving the pen controlling mechanism, provides a smoothly running, efficient machine and eliminates the necessity for interchanging gears for different machine speeds. The essential idea back of our improvements has been to lighten the movements and reduce the inertia of the moving parts of the machine.

Our invention will best be understood and appreciated from the following description of a preferred embodiment thereof, selected for purposes of illustration and shown in the accompanying drawings in which:

Fig. 1 is a view in side elevation of that por-

tion of a paper ruling machine with which our invention is concerned,

Fig. 2 is a view in perspective of the driving mechanism of the machine,

Fig. 3 is a plan view of a portion of the machine,

Fig. 4 is a view in side elevation corresponding to Fig. 3,

Fig. 5 is a view in perspective corresponding to Figs. 3 and 4,

Fig. 6 is a view in cross section of a cam wheel and its associated gear,

Fig. 7 is a view in cross section taken through a pen clamp,

Fig. 8 is a view in perspective of a pen beam and associated elements,

Fig. 9 is a view in perspective showing the lay boy,

Fig. 10 is a view in side elevation of the gearing for the cam wheels, the gear housing being broken away,

Fig. 11 is a plan view showing the general organization of the machine, and

Fig. 12 is a view in perspective of one corner of the machine.

Before proceeding to describe the details of the machine shown in the drawings we shall present a brief outline of its general construction and organization. The machine is contained within and supported by a long rectangular frame 20 of heavy metal and considerably longer than it is wide. By means of mechanism not here shown but including a driven feed tape or tapes 274, sheets of paper are taken from a stack and advanced one by one on the surface of a cloth belt 182 to a gate 102 where each one is momentarily checked and straightened. The sheets are then successively conveyed on the cloth belt or apron 182 running at a carefully predetermined speed beneath a series of endless strings 210 which keep the sheets flat on the cloth 182. Poised over the sheets as they are advanced by the cloth belt 182 are a plurality of pens 194 held in transverse clamps and these are lowered and raised in accordance with the length of the lines to be ruled on each sheet. Means are provided for raising and lowering certain of the pens 194 held in a clamp without affecting the position of the other pens in the clamp, such means being universally termed an "underlift." After the pens have done their work on a sheet, the sheet is passed under a heater to dry the ink, and the sheets are finally removed at the far end of the machine by a lay boy which ensures their delivery into a receiving bin.

Our invention, as previously stated, has for its most important object to increase the production of paper ruling machines, and we have secured the desired result by improving the drive for the cloth belt 182 and for the mechanism for raising and lowering the pens, the pen clamps, and the lay boy. The aforesaid improvements, although directed to different elements of the machine, co-act to make increased production possible.

The improved drive can best be seen in Fig. 2 in which an L-shaped metal base 24 is shown as provided with an integral arm 26 hooked at its outer end to fit over a lower cross girt 22 of the frame, the base 24 being grooved to fit over another cross girt 22. A threaded socket in the base 24 receives a threaded rod 28 which extends out through the frame 23 and is held against longitudinal movement by a pair of collars 32. A hand wheel 30 is provided for turning the rod 28 and sliding the base 24 along the cross girts 22. Bolted to the base 24 is a motor 34 which, through a belt 40, drives a suction blower pump 36 also bolted to the base 24. The motor 34 also drives a variable speed transmission device of the Reeves type, including a pair of disks 42 secured to the motor shaft and having opposed convex faces. The outer disk is keyed to the motor shaft and free to slide longitudinally upon it, being urged toward the other disk by a heavy spring 43. Secured to the outside of the frame 20 are a bracket 44 and a housing 48. A short shaft 46 is journaled in the bracket and in the near wall of the housing 48. A pulley 50 is coupled to the shaft 46 through a conventional clutch 52 and driven from the Reeves transmission by a belt 54. It will be apparent that the speed of the pulley 50 is increased when the base 24 is pulled towards the pulley 50 and vice versa. Fast on the shaft 46 is a pinion 56 which meshes with a gear 58 secured to a shaft 60 journaled in a bearing bracket 62 on the inside of the frame 20 and in the housing 48.

The pump 36 operates a sheet feeding system of the type disclosed in U. S. Letters Patent No. 2,070,860 granted July 1, 1935, on an application of R. T. Duffy and in the co-pending application of Charles E. Clarke Ser. No. 231,495, filed September 24, 1938. The pump 36 is secured to the base 24 and moves with it so that its operation is in no way affected when the base is moved to vary the speed of the belt 54.

Within the housing 48 and secured to the shaft 60 is a gear (not shown) in mesh with another gear 64 secured to a shaft 66 journaled in the housing 48 and in a bearing bracket and gear housing 68. Motion of the shaft 66 is transmitted through bevel gears in the housing 68 to a shaft 70 running transversely across the frame 20 and journaled in a housing 72 on the other side of the frame 20. Within the housing 72 is a gear 74 secured to the shaft 70 and driving two gears 84 and 86 directly and a gear 90 through a smaller intermediate gear 88 in mesh with the gear 86. The gears 84, 86, 88 and 90 turn on studs 76, 78, 80 and 82 respectively, journaled in the housing 72. The studs 76, 78 and 82 extend through the housing and carry cam disks 92, 94, and 96 which control the pen clamps and the underlifts as will be later explained. It will now be seen that the cam disks controlling the pen clamps are driven through fixed gearing from the Reeves transmission and that the rate of rotation of the cam disks can only be varied by manipulation of the hand wheel 30.

Fast to the shaft 60 and within the housing 48 is a series of gears (not shown) of different diameters. A gear on a pivoted arm may be moved selectively to engage one of the gears on the shaft 60, by means of the handle 228. The movable gear is in mesh with a gear on a shaft 280 to the end of which is secured a bevel gear (not shown) contained within a housing 49 secured to the frame 20. The motion of the shaft 280 is transmitted through bevel gears in the housing 49 to a series of gears in a casing 230 secured to the inside of the frame 20. The last gear in the train of gears in the casing 230 is secured to a shaft which carries a transverse roll 232 of large diameter around which is passed a wide cloth belt or apron 182. The belt 182 moves along the surface of a convex bed 180 secured within the frame 20 and preferably made of wood or other light material. At its further or delivery end the belt 182 passes over a roll 242. The shaft for the roll 232 is geared to a shaft 288 disposed above it and transversely of the frame 20. A heavy roll 231 is carried on the shaft 288 and cooperates with the roll 232 to feed the sheets onto the moving cloth belt 182. The belt 182 and the rolls may be turned by means of a hand wheel 234 secured to the end of the shaft 288 in setting up or adjusting the machine.

Supported on the frame 20 is a pair of standards 208 which in turn support transverse rollers 209. In the base of the standard 208 at the delivery end of the machine is a roll 211 and supported adjacent the base of the standard 208 at the near end of the machine is a plurality of grooved guide rollers 278 carried on a shaft 276. A number of endless strings or threads are carried by the standards and rollers and the strings pass over the roll 232, passing under the guides 278, and the motion of the roll 232 causes the strings to move at the same rate as the cloth belt 182. Thus it will be seen that sheets of paper are taken from a stack (by means of mechanism not shown) and disposed upon moving tapes 274 which bring the sheets to the bite of the rolls 232 and 234 so that the strings 210 and the belt 182 cooperate to advance the sheets over the bed 180. The strings 210 also act to keep the sheets flat on the cloth belt 182 during the ruling operation. Transverse tension bars 236 are carried in the frame 20 and eccentrically mounted. The bars 236 may be adjusted to impart any degree of desired tension to the cloth belt 182 and to raise or lower it with respect to the strings 210.

The drive for the machine, as above described, begins with the motor 34 which drives the cam disks directly from the Reeves transmission, and a branch drive works through the change speed system in the casing 218 to the cloth rolls and the string rolls. The feeding mechanism (not shown) is also operated through the change speed system from the shafts 240 and 241. It will be apparent that the speed of the cam disks controls the striking of the pens, the most important movement in the machine. The change speed system in the casing 48 determines the rate of what might be termed the auxiliary motions of the machine, namely the feeding and conveying mechanism. By means of our drive the speed of the cam disks is controlled through the Reeves transmission, and any necessary compensating in the auxiliary motions can be made through the change speed system in the branch drive. A register roll 212 is carried in the frame 20 over the strings 210 and

is eccentrically mounted. The roll 212 may be adjusted to change the tension of the threads 210 on the cloth 182. The roll 211 may also be adjusted by means of a thumb screw 238 connected to the shaft for the roll and working in the base of the standard 208.

A toothed gate 102 is pivotally mounted and extends across the frame 20 over the strings and the cloth, and a lever 100 connected to the gate 102 is reciprocated by a cam 98 fast on the end of the shaft 70. By means of the cam 98 and the lever 100 the gate 102 is caused intermittently to swing into contact with the cloth belt 182, its function being momentarily to check the oncoming sheets of paper and align them exactly before they reach the pens.

The pump 36 operates a vacuum feed system including a flexible conduit 226 provided at one end with a bleeder valve in a housing 224 secured to the casing 48. The valve in the housing 224 is operated by a plunger 220 controlled by a cam 218 secured to a shaft 216 disposed transversely of the machine and operated by a handle 214. When the machine is shut down after a run, the handle 214 is moved to open the valve and relieve the vacuum. A shaft 240, which is coupled to the shaft 66, operates the timing valve (not shown) for the vacuum feed device above referred to, and the shaft 241 coupled to the shaft 280 operates the sheet conveying tapes 274.

By reference to Figs. 5 and 6, it will be seen that the cam disk 92 is provided with concentric grooves 108 cut into its inner and outer side faces and accessible through a slot 110 in the periphery of the cam disk 92. The grooves are adapted to receive two or more cams or dogs of two different types. One is a pickup cam 112 which has a base that may be bolted in fixed position in one of the grooves 108 and a raised and pointed striking section or ear closely hugging the face of the cam disk. The other is a drop cam 114 which is similar to the pickup cam except that its pointed ear is offset from the face of the cam disk 92. Secured to the upper members of the frame 20 are oppositely disposed carriages 116 and 122 having bearings 118 for a rod 120 disposed transversely above the cloth belt 182. At one end of the rod 120 is secured a bracket 124 which has journals for two other transverse shafts 126 and 128 and corresponds in this respect to a bearing bracket 125 secured near the opposite end of the rod 120. Torsion springs 198 and 200 force the shafts 128 and 126 to turn in a clockwise direction. The bracket 124, however, has a long extension ending in a short bar 132 and a fork acting as a pivot mount for a key 134. Pivotal mounted on the outer end of the bar 132 is a latch 136 having a shoulder near its free end, and a similar latch 138 is pivotally secured to the inner end of the bar 132. Helical springs 140 on the bar 132 urge the latches 136 and 138 to swing in clockwise direction. The bracket 116 has an integral extension 142 directly beneath the end of the extension of the bracket 124 and a stop bolt 144 bears thereon and provides means for adjusting the height of the assembly on the bracket 124 which is provided with opposed feet 146 extending below and to both sides thereof.

A link 148 ends in a yoke 149 loose on the end of the shaft 128 and extends outwardly and beneath the bar 132. A block 150 is set in the outer end of the link 148 and is provided with a downwardly extending pointed ear 151 and a

lug 152 set in its outer face. A stop bolt 154 in the end of the link 148 permits adjustment of the height thereof from the extension 142. A lever 158 is fast at one end to the shaft 128 between the arms of the yoke 149 and carries a stop bolt 160 bearing on a lug 156 set in the link 148; a lever 162 permits locking the stop bolt 160 in desired vertical position. The foregoing elements are arranged so that the ear of a pick-up cam 112 will strike the ear 151 and lift it, thus lifting the link 148; the latch 136 is forced in clockwise direction by the spring 140 until the lug 152 is caught on the shoulder of the latch, thus holding the link in elevated position. When the link 148 is lifted, the lug 156 forces the bolt 160 and its associated lever 158 upwardly, thus turning the shaft 128 in counterclockwise direction and lifting the pen clamp into inoperative position. When a drop cam 114 strikes the latch 136 the lug 152 is released, and the link 148 and the shaft 128 resume their former positions and the pens are returned to their operative positions or strike. The duration of the periods during which the link 108 is held in raised or lowered position is primarily determined by the setting of the Reeves transmission, which controls the rate of rotation of the cam disks, and secondarily determined by the position of the pick-up cams and drop cams in the groove 108 of the cam disks. The number of cams which may be used is not limited and the link 148 can be raised and lowered several times during one revolution of the cam disk 92 if that is desired.

The action of the cams on the inside of the cam disk 92 is identical with the movements just described. A link 164 is provided with a yoke 165 free on the shaft 126 and has a block at its outer end similar to the block 150 and provided with a lug 168. A stop bolt 170 is carried by the end of the link 164 which cooperates through a lug 172 with a stop bolt 176 carried by a lever 174 which is secured to the shaft 126 between the arms of the yoke 165. The stop bolt 176 is tightened by means of a handle 178.

A handle 175 is carried on the outer end of the bar 132 and by this the whole assembly above the cam disk 92 may be raised by the operator and temporarily rendered inoperative. The feet 146 carry the links 148 and 164 upwardly and remove the lugs 152 and 168 from the path of the cams, and the key 134 falls naturally into a position where it bears on the extension 142. Thus by raising the handle 175, the key 134 falls into place and when the handle 175 is lowered again, the key 134 bears on the extension 142 and renders the cams and latches inoperative. A reinforcing bearing bracket 130 clamps the three shafts 120, 126, and 128 firmly together and prevents relative lateral movement thereof.

The shaft 128 may be termed the "pen clamp shaft," since it is secured by a bracket 196, to a pen clamp which may be of the construction illustrated in Fig. 7. The pen clamp, in its preferred form, consists in a long light wooden upper bar 184 curved at its forward edge to supplement a similar curve in the forward edge of a light underlying wooden member 186. Opening into the under face of the upper member 184 are a number of sockets 188 for bolts 190 screwed up through and fast in the lower member 186, and each socket has a hole in its rear side for a long thumb screw 192 having a tapered end. Each bolt 190 has a taper hole fitting the point of a thumb screw 192. Thus, when the thumb

screws 192 are turned in, the points enter the taper holes in the bolts 190 and each bolt acts to draw together the sections of the upper and lower member adjacent to it. A series of flexible pens 194 may be arranged in desired locations along the pin clamp and between the members thereof, the thumb screws being individually operable to release any selected pen or pens.

At this point it should be noted that we have omitted the conventional metal pen beam and secured the light pen clamp directly to the shaft 128. This results in lightening the work of the cams, eliminating vibrations in the machine which would otherwise oscillate or disturb the pens, and permits the machine to be run at relatively high speeds without impairing the accuracy of the striking of the pens 194.

The shaft 126 is flattened on one side and to it underlifts are secured. Each underlift comprises an elongated spatulate finger 202 hooked at its inner end to fit over the shaft 126 and provided with a pair of adjusting bolts 204 and 206 bearing on the flattened face of the shaft 126 and by means of which the underlift may be clamped at any desired angle. Underlifts may be placed on the shaft 126 in any desired combination. For example, there may be five pens in the pen clamp and underlifts disposed under two of them. When the cam disk 92 rotates, the outside cams raise and lower the pen clamp with all five pens at predetermined intervals, whereas the inside cams affect only the two pens provided with underlifts.

The lay boy at the discharge end of the machine will now be described with particular reference to Figs. 9 and 11. This mechanism is designed to impart to the sheet being delivered a longitudinally curved configuration, thereby stiffening the sheet and insuring delivery without danger of buckling. The mechanism now to be described is designed to impart a compound longitudinal curvature to the sheet by lifting its marginal edges and its central portion and depressing or holding down the sheet along lines spaced within its marginal edges. The sheet has thus imparted to it a central convex curvature merging into two parallel concave curvatures.

Referring to Figs. 9 and 11, it will be seen that a pair of longitudinally adjustable carriages 248 are mounted opposite to each other upon the side frames 20. In these carriages are journaled the transverse cloth rolls 242 and 244, the ruled sheets passing over the roll 242 in leaving the machine. The carriages are each provided with an upright standard or bracket 250 and between these brackets extends a stationary supporting rod 252. Mounted to rock freely upon the supporting rod 252 is a pair of heads 262 each provided with an upstanding spindle 264. An angular arm 254 provided with a hub 266 is rigidly but adjustably secured to each spindle 264. Each arm 254 extends horizontally and then downwardly at an inclination, being provided at its lower end with bearings for a crowned guide roll 256. The heads 262 may be adjusted transversely upon the supporting rod 252 in accordance with the width of the sheet to be handled and all positions of adjustment are so located that the guide wheels 256 run upon the sheets carried by the cloth 182 as they pass over the cloth roll 242. The arms 254 are set so that the guide rolls 256 rotate in slightly divergent planes thus tending to spread the sheet under light tension between them.

Each arm 254 carries a curved downwardly ex- 75

tending bracket 258 provided at its lower end with an outwardly inclined elongated guide plate or scoop 260 which is disposed with its inner edge practically in contact with the surface of the apron 182. It will be understood that each arm 254 with its associated guide roll and scoop rest by their own weight upon the apron 182 or upon the sheet carried by the same.

A transverse supporting rod 263 extends between the side frames 20 just beyond and below the cloth roll 242. Adjustably secured to the rod 263 is a center guide bar or finger 270 which extends rearwardly close to the surface of the apron 182 and midway between the two scoops 260. The guide bar 270 tapers inwardly, its inner or advanced edge being beveled to pass under the advancing edge of the sheets and to deflect each sheet progressively more and more into upwardly convex curvature as the sheet advances to the point of delivery. The inner ends of the scoops 260 are also beveled to a point and thus are arranged to pick up the margins of the advancing sheets and lift them above the surface of the apron, while in adjacent lines the guide rolls 256 hold the body of the sheet down upon the surface of the apron 182. It will thus be seen that the scoops 260, the guide bar 270, and the guide rolls 256 cooperate to impart a compound curvature to the sheet, the crest of the central curve being above the guide bar 270 and the valleys of the concave curves being beneath the guide rolls 256. The sheet is thus stiffened longitudinally and in that condition is passed accurately out of the machine.

From the foregoing description of one embodiment of our invention it will be apparent that we have provided a smooth and efficient drive for the mechanisms of the machine, lightened the pen clamp, introduced a lighter and more efficient cam-operated pen controlling mechanism, and improved the lay-boy to ensure rapid and accurate delivery of the ruled sheets. Incidentally the underlifts have been improved and more accurate adjustment thereof made possible. A machine of the type illustrated in the drawings has been successfully operated at the hitherto unheard of rate of 5,000 sheets, or 10 reams, per hour. Although a single machine has been shown in the drawings, the invention has been successfully applied to a duplex machine in which the pens of either member of the machine may be operated for feint lining or for striking.

Having thus described our invention we claim as new and desire to secure by Letters Patent of the United States—

1. Pen clamp operating mechanism for paper ruling machines, which comprises a pen clamp, a shaft fast to said pen clamp, an arm secured to said shaft, a pointed ear secured to said arm, a cam disk, a pointed cam secured to said cam disk and arranged to strike said ear to lift said arm and turn said shaft to lift the pen clamp, means independent of the cam and cam disk for holding the pen clamp in raised position, and a second cam on the cam disk and having a pointed offset portion arranged to release the holding means and permit the pen clamp to drop.

2. An underlift for ruling machines, comprising an elongated spatulate finger provided with a hook at its base, and a pair of adjusting bolts threaded in the hook.

3. An underlift for ruling machines comprising a flattened shaft, an elongated finger provided with a hook, and a pair of adjusting bolts threaded through the hook, whereby the hook may be

slipped over the shaft and the finger fixed at any desired angle on the shaft by manipulation of the adjusting bolts.

4. In a paper ruling machine including sheet feeding and conveying mechanisms, the combination of a frame, a rod disposed transversely across the frame, a bearing bracket fast on each end of said rod, a rock shaft journaled in said bearing bracket, a pen clamp secured to said rock shaft and movable therewith, a cam wheel mounted on the frame and provided with a marginal slot, a first cam secured in said groove and having a pointed ear set close to the surface of the cam wheel, a second cam secured in said groove and having a pointed ear offset from the surface of the cam wheel, a link mounted at one end on said rock shaft and having at its free end a pointed cam follower overhanging the path of the ear of the first cam, an extension integral with said bearing bracket and overhanging the cam wheel, a spring loaded latch pivotally mounted on said extension and disposed in the path of the ear of the second cam, and a lug on the cam follower disposed to be engaged by said latch, whereby during rotation of the cam wheel the first cam raises the cam follower to cause the latch to engage the lug and also to rock the pen clamp, and the second cam disengages the latch without touching the cam follower.

5. In a paper ruling machine including sheet conveying mechanism and a pen clamp; the combination of a shaft fast to said pen clamp, a link secured to said shaft, a spring loaded latch disposed adjacent the free end of said link, a lug secured to the free end of said link, a cam disk disposed below the free end of said link, a block fast to said link and having a downwardly extending pointed ear, a series of pointed cams disposed on the cam disk some of which are arranged to strike the pointed ear of said block to lift the link and pen clamp and other cams being arranged to strike the latch without touching the pointed ear.

6. In a paper ruling machine including a pen clamp, the combination of a shaft fast to said pen clamp, an arm secured to said shaft, a cam disk disposed beneath the outer end of said arm, a downwardly extending pointed ear fast to the outer end of said arm, a pointed cam secured to said cam disk and arranged to strike said ear as the disk is rotated, a lug disposed on said arm and extending beyond the ear, a second pointed cam offset from the surface of the disk and secured to said disk, and a spring loaded latch disposed in the path of said second cam adjacent the outer end of said arm and movable to engage the lug and hold the arm and pen clamp elevated until the second cam disengages the latch from the lug.

7. A paper ruling machine, which comprises a frame, a pen clamp disposed transversely across the frame, a shaft fast to said pen clamp and journaled at the sides of the frame, an arm secured to the shaft and having its outer end extending beyond the frame, a cam disk rotatably mounted outside of the frame and underlying the end of the arm, a downwardly extending pointed ear secured to the end of said arm, a pointed cam secured on the cam disk and striking in its path the pointed ear, a lug secured to the ear, a second pointed cam recessed to avoid striking the ear, a latch disposed adjacent the outer end of the arm and arranged to engage the lug on the ear, the latch lying in the path of the second pointed cam.

8. A paper ruling machine, which comprises a frame, a pen clamp disposed transversely across the frame, a shaft fast to said pen clamp and journaled at the sides of the frame, a spring connected to said shaft and resisting rotating thereof, an arm secured to the shaft and having its outer end extending beyond the frame, a cam disk rotatably mounted outside of the frame and underlying the end of the arm, a downwardly extending pointed ear secured to the end of said arm, a pointed cam secured on the cam disk and striking in its path the pointed ear, a lug secured to the ear, a second pointed cam recessed to avoid striking the ear, a latch disposed adjacent the outer end of the arm and arranged to engage the lug on the ear, the latch lying in the path of the second pointed cam.

9. In a paper ruling machine the combination of a frame, a bearing bracket mounted on the frame, a shaft rotatably journaled in the bracket, an arm secured to said shaft at the side of the frame, a second shaft journaled in said arm, a pen clamp fast to said second shaft, a third shaft also journaled in said arm, underlifts secured to said third shaft, a second arm fast to said second shaft and parallel to the first arm, a third arm fast to said third shaft and parallel to the first arm on the opposite side from the second arm, a cam disk underlying the ends of said three arms and rotatably mounted outside said frame, downwardly extending ears carried on the ends of said second and third arms, lugs on said ears, spring loaded latches pivotally mounted on the end of the first arm and arranged to engage the lugs on the ears, a cam on each side of the cam disk arranged to strike said ears, and other cams on each cam disk arranged to avoid the ears and strike the latches.

10. The structure recited in claim 9 and in addition thereto, means for holding said ears out of engagement with the cams.

11. In a paper ruling machine including a pen clamp, and a pen clamp shaft; the combination of an arm secured at one end to said shaft, a cam disk rotatably mounted below the end of the shaft, a pointed block depending from said arm, a lug on the outside face of the block, a cam adjustably secured on the outer surface of the cam disk and having a pointed portion hugging the face of the disk and arranged to strike the pointed block to lift the arm and the pen clamp, a latch pivotally mounted near the block and arranged to engage the lug when the cam has raised the block, and a second cam adjustably secured on the cam disk and having an offset portion arranged to avoid the block but strike the latch and release the arm to lower the pen clamp.

12. In a paper ruling machine, a pen clamp, an arm for raising or lowering said pen clamp, a pointed block disposed on the free end of the arm, a cam disk disposed for rotation below the block, a lug fast on the block, a latch arranged to engage the lug and hold the arm elevated, a cam secured to the cam disk and dimensioned to lift the block and arm just high enough for the latch to engage the lug, and a second cam secured to the disk and arranged to strike only the latch to disengage it from the lug.

13. In a paper ruling machine the combination of a pen clamp, a shaft fast to the pen clamp, a long yoke freely mounted on the shaft and having a lug integral therewith, a short arm fast to the shaft between the arms of the yoke, a bolt threaded through the arm and bearing on said lug, and arms disposed adjacent the free end of the

yoke for raising and lowering it, the bolt serving to turn the shaft relative to the yoke.

14. In a ruling machine, a pen clamp, an arm for lifting the pen clamp, a cam disk adjacent to the end of the arm and located in front of said pen clamp, a latch disposed to engage the arm when the pen clamp is lifted, and a pair of cams secured to said cam disk and arranged to rotate in parallel, non-coincident paths for actuating the arm and latch respectively to raise 10 and lower the pen clamp.

15. In a ruling machine, a frame, a shaft disposed across the frame, a bracket secured at one side of the frame and providing a journal for the shaft, an arm fast to the shaft and disposed substantially parallel to the frame, a latch movable upon the bracket for engaging the arm, and rotatable means secured to the frame successively for lifting the arm and rocking the shaft and for disengaging the latch from the arm.

16. In a ruling machine, a pen clamp, a bracket in which said pen clamp is pivotally mounted, an arm adjacent said bracket controlling the elevation of the pen clamp, rotatable means for raising the arm, a latch secured to the bracket and movable to engage the lifted arm, and means for disengaging the latch to allow the arm to drop.

17. In a ruling machine, a frame, a pen clamp pivotally mounted across said frame, a pair of brackets pivotally mounted at the sides of the frame to carry the pen clamp, an extension integral with one of said brackets, an arm disposed in juxtaposition to the extension and controlling

the elevation of the pen clamp, a latch movable on said extension, adjustable means for lifting said arm and causing the latch to engage the arm and hold it elevated, and adjustable latch disengaging means for dropping said arm.

18. In a ruling machine, a frame, a bracket secured to one side of said frame, a shaft journalled in said bracket, a pen clamp fast to said shaft and disposed over said frame, an arm fast to said shaft at the side of the frame, a latch secured to the bracket and movable to engage the arm, and cams movable in parallel non-coincident paths for first lifting the arm to cause the latch to engage the arm and then disengaging the latch to drop the arm.

19. In a ruling machine, a frame, a pair of brackets pivotally mounted at opposite sides of the frame, an underlift shaft and a pen clamp shaft rotatably supported by said brackets, an arm secured to the underlift shaft, an arm secured to said pen clamp shaft in parallel relation with the first arm, a disk underlying the extremities of said arms and secured to the frame in advance of said brackets, means secured to said disk for controlling the elevation of the first arm and independent means also secured to the disk for controlling the elevation of the second arm, and means for holding the arms out of reach of the elevation controlling means when the brackets are pivoted upwardly to a predetermined position.
